ELIZA JANE JEWELL, OF BROOKLYN, NEW YORK, ADMINISTRATRIX OF
THE ESTATE OF THEODORE E. JEWELL, DECEASED.

Letters Patent No. 70,855, dated November 12, 1867.

IMPROVED YOKE FOR GRAIN-ELEVATORS.

The Schedule referred to in these Letters Patent and making part of the same.

TO ALL WHOM IT MAY CONCERN:

Be it known that THEODORE E. JEWELL, deceased, late of Brooklyn, Kings county, New York, did during his lifetime invent a new and improved Yoke for Grain-Elevators; and I, ELIZA JANE JEWELL, of Brooklyn, aforesaid, administratrix of the estate of said THEODORE E. JEWELL, do hereby declare that the following is a full, clear, and exact description thereof, which will enable others skilled in the art to make and use the same, reference being had to the accompanying drawings, forming a part of this specification, in which—

Figure 1 represents a sectional side elevation of this improved grain-elevator.

Figure 2 is an end elevation of the same.

Figure 3 is a detail horizontal sectional view of the same, the plane of section being indicated by the line *z z*, fig. 2.

Similar letters of reference indicate corresponding parts.

This invention relates to a new manner of constructing and arranging the sliding yoke of a grain-elevator, and consists first in making the yoke of cast iron instead of wood, as is heretofore always done; and second, in the use of adjustable guides between the yoke and the wooden frame, whereby the yoke can be accurately fitted between the frame, so as to slide freely, and whereby inequalities arising from the expansion or contraction of the frame or yoke, or either, can be regulated.

A represents the stationary frame of an elevator, to be secured near the edge of a pier or wharf. B is the sliding yoke, suspended by means of a rope, I, from the upper part of the frame A, and carrying the shaft C, over which the elevator-apron D passes in a case, E, and upon which a pulley, F, is mounted, by means of which it receives its motion from a band, G. The yoke B is made of cast iron, and the bearings for the shaft C and for the friction-pulleys H H, by which the belt is stretched, are secured to it, as is clearly shown in fig. 1. The yoke is fitted between two upright posts *a a* of the frame A, said posts being provided with projecting tenons *b b*, on their inner sides. The yoke is provided with a flange, *c*, on each end, said flange lapping over one side of the tenon *b*, (see fig. 3.) By means of bolts *d d*, plates *e e* are secured to the flanges *c*, said plates overlapping the other side of tenon *b*, so that the latter is fitted between the flanges *c* and plates *e*, as shown. The bolts *d* pass through lugs *i i*, projecting from the end of the yoke. Between the flanges *c* and plates *e*, and between two lugs *i i*, are inserted gibs or bars *f*, which are held in place by the lugs *i i*, of which one is above and the other below each gib, as in fig. 2. The gibs *f* form the bearings of the yoke against the tenons *b*, and can be adjusted towards or from the tenons by means of set-screws *g*, which pass through the plates *h*, forming the edges of the yoke, as is clearly shown in figs. 2 and 3. As the tenons swell or shrink, the gibs are adjusted by means of the set-screws *g*, so as to make the yoke slide freely, without allowing the same too much play. The gibs can be made of wood or metal, as may be desired.

The main advantage of this invention is, that when the guides *f* are worn, they can be removed by taking off the nuts *d* and plates *e*, and can then be replaced by new ones, without even taking the yoke off the frame, while the yokes now in use become useless as soon as the edges are worn. The lugs *i* may reach to the tenon if desired, but I prefer to have them not reach the same, so that only the gibs are in contact with the tenons *b*.

Having thus described the invention, what I claim as new, and desire to secure by Letters Patent, is—

1. Making the yokes of grain-elevators of cast iron, constructed substantially as and for the purpose herein shown and described.
2. The adjustable guide arrangement at the ends of a metal yoke, when consisting of the flanges *c*, plates *e*, gibs or guides *f*, and set-screws *g*, all made and operating substantially as described, in combination with the tenons *b* on the uprights of the stationary frame A, arranged as described.

ELIZA JANE JEWELL,
Administratrix of the Estate of T. E. Jewell, deceased.
